UNITED STATES PATENT OFFICE.

RICHARD H. WILMER, OF SHANDON, OHIO.

STAMP-MOISTENER.

1,076,930.

Specification of Letters Patent.

Patented Oct. 28, 1913.

Application filed September 11, 1912. Serial No. 719,844.

To all whom it may concern:

Be it known that I, RICHARD H. WILMER, a citizen of the United States, residing at Shandon, in the county of Butler and State 5 of Ohio, have invented certain new and useful Improvements in Stamp-Moisteners, of which the following is a specification, reference being had to the accompanying drawings.

10 This invention relates to new and useful improvements in stamp moisteners and has for its object to provide a device so as to enable one to quickly and readily moisten any number of stamps without using the 15 saliva in the mouth.

A further object of the invention resides in providing a device which can be readily carried about the person and a still further object resides in providing a device which is 20 supplied with a device for raising the stamp, whereby the same may be readily removed after being moistened.

A still further object resides in providing a device which is extremely simple and durable in construction, inexpensive to manufacture and one which will be very efficient 25 and useful in operation.

With these and other objects in view, the invention consists in the novel features of 30 construction, combination and arrangement of parts as will be hereinafter referred to and more particularly pointed out in the specification and claims.

In the accompanying drawing forming a 35 part of this application, Figure 1 is a perspective view showing my device applied to the hand of a person. Fig. 2 is a vertical longitudinal section through the device. Fig. 3 is a vertical transverse section there- 40 through; and Fig. 4 is a perspective view of the operating means for raising the stamp after moistening the same.

In describing my invention, I shall refer to the drawing in which similar reference 45 characters designate corresponding parts throughout the several views and in which—

1 indicates a base plate formed of leather, cardboard, metal or any other desired material, the same being of a convenient size to 50 be applied to the back of a hand and mounted thereon is a pad 2 formed of cotton, wool, sponge or any other desired material which will retain a liquid. Engaged with the one 55 end of the base plate 1 is a flexible connection 3 which, after being formed into a loop is slidably disposed through the plate

1 and pad 2 at the opposite end thereof and the extreme free end of said connection, after being fastened properly about the hand of the user, is adapted to be engaged 60 with a hook or the like 4 carried at the opposite end of the plate 1, on the side thereof opposed to that from which the opposite end of the flexible connection 3 extends.

Extending transversely and centrally of 65 the device and oscillatingly mounted between the base plate 1 and the pad 2, is a shaft 5, the ends of which are bent upwardly and hooked to form eyes 6 and engaged with these eyes 6, is an endless flexible connection 7. The material forming the eye on the one upwardly bent end of the shaft 5, is continued downwardly and bent to form an operating lever or the like 8, whereby said shaft 5 may be oscillated on the device and 70 the flexible connection 7 lowered toward the 75 pad or raised thereabove, as desired.

In practice, the device is applied to the back of the one hand, as shown in Fig. 1, the flexible connection 3 being engaged with 80 the fingers, as shown, and drawn about the wrist, so as to allow one end of said flexible connection to be engaged with the hook 4. The lever 8 is then drawn upwardly so as to 85 allow the flexible connection 7 to be forced against the pad 2 and a stamp may then be placed upon the pad over said flexible connection. It will be understood, of course, that said pad has been previously supplied with water and after the stamp has been 90 placed on the pad, the lever is pressed downwardly, which will cause the flexible connection 7 to be raised upwardly and correspondingly carry the stamp therewith, whereby the latter may be readily grasped to 95 be placed upon an envelop. This operation may be continued and numerous stamps readily moistened without the necessity of applying the tongue thereto. Should it be desired to moisten an envelop, the same may 100 be readily accomplished by merely lowering the flexible connection 7 against the pad 2 and allowing the gummed portion of the envelop to be passed over said pad in the usual manner.

105 From the foregoing it will be seen that I have provided a device which is extremely simple and durable in construction, inexpensive to manufacture and one which will be very efficient and useful in operation, 110 and while I have particularly described the elements best adapted to perform the func-

tions set forth, it is obvious that various changes in form, proportion, and in the minor details of construction may be resorted to without departing from the spirit or 5 sacrificing any of the principles of the invention.

Having thus described this invention, what I claim is:—

A stamp moistener comprising a base 10 plate, a pad applied thereto, a shaft mounted to oscillate between said pad and base plate and extending transversely thereof, the ends of said shaft being bent upwardly to project above the upper face of the pad,

flexible connecting means between the upwardly bent ends of said shaft, and a lever arm formed from a continuation of one of the upwardly bent arms of said shaft, whereby said shaft may be rocked and the flexible connecting means raised and lowered.

In testimony whereof I hereunto affix my signature in the presence of two witnesses.

RICHARD H. WILMER.
